UNITED STATES PATENT OFFICE.

GEORGE W. DREW, OF WASHINGTON, DISTRICT OF COLUMBIA.

DESIGN FOR A STEAM-BOILER FRONT.

SPECIFICATION forming part of Design No. 17,941, dated December 13, 1887.

Application filed November 3, 1887. Serial No. 254,929. Term of patent 3½ years.

To all whom it may concern:

Be it known that I, GEORGE W. DREW, a citizen of the United States, residing at Washington, in the District of Columbia, have invented and produced a new and original Design for Steam-Boiler Fronts, of which the following is a specification, reference being had to the accompanying drawings, forming part thereof, in which—

10 Figure 1 is a front elevation of my newly-designed boiler-front, and Fig. 2 an enlarged section taken on line $x x$ of Fig. 1.

Referring to said drawings, A is the boiler-front, consisting of a plane surface having parallel sides $A' A'$, a straight base, A^2 , and a curved top, A^3 , the upper corners, $a a$, and lower corners, $a' a'$, being extended beyond the sides.

20 $a^2 a^2$ are semicircular projections from the sides at about the center of the same.

Below the curved top line, at the center of the front, is a raised circle, B. On either side of this circle are substantially triangular raised figures $B' B'$, the bases of the same being in line with each other, the sides of said triangular figures adjacent to the circle being concave and concentric with said circle, the other sides of the figures $B' B'$ having semicircular projections $b b$.

30 C represents the main doors of the boiler, D the grate-doors, and E the ash-pit doors. Said doors are rectangular in form, and are provided at their tops and bottoms with curved extensions F and on their sides adjacent to the sides of the front with curved extensions f. Each of said doors is provided with strap-hinges G, one strap of each hinge being secured to one of the curved extensions f, the pintle of each hinge being provided with a

40 head substantially in the form of an acorn. Around the edges of the doors C, D, and E are formed moldings H, consisting of parallel ribs or corrugations, (shown in section in Fig. 2,) said molding forming a framing for the panels I, which consist of plane surfaces ornamented by raised rectangular figures K, representing chain-work, the links of the chain

being rectangular in form and having L-shaped corner links.

On the front, at the sides of the grate and ash-pit doors, are raised web-shaped figures $L L$ and $L' L'$, the larger ends of the figures being curved and approximate to each other, said figures being provided near their points with projections l and l'. Between the figures $L L$ and $L' L'$ are raised semicircular figures O O.

I claim—

1. In a design for a steam-boiler front, the front plate, A, having parallel sides $A' A'$, straight base A^2 , curved top A^3 , extended corners $a a$ and $a' a'$, and semicircular side projections, $a^2 a^2$, the surface of said front plate, A, being ornamented with the raised circle B, raised triangular figures $B' B'$, the raised wedge-shaped figures $L L$ and $L' L'$, and raised semicircular figures O O, arranged and disposed substantially as shown and described.

2. The design for a steam-boiler front, consisting of the front plate, A, having parallel sides $A' A'$, straight base A^2 , curved top A^3 , extending corners $a a$ and $a' a'$, and semicircular side projections, $a^2 a^2$, the surface of said front plate, A, being ornamented with the raised circle B, raised triangular figures $B' B'$, raised wedge-shaped figures $L L$ and $L' L'$, and semicircular figures O O, and the doors C, D, and E, having the molding H around the edges of the same, and the panels I, ornamented with the rectangular figure K, representing chain-work, all arranged and disposed substantially as shown and described.

3. In a design for a door for steam-boiler fronts, a rectangular door having at its top and bottom curved extensions F F and at one side curved extensions f f, the molding H around the edge of the door, and panel I, ornamented with a rectangular figure, K, representing chain-work, substantially as shown and described.

GEORGE W. DREW.
